Signed and Sealed

UNITED STATES PATENT OFFICE.

CARL J. HOFMANN, OF NEW YORK, N. Y., ASSIGNEE OF ONE-HALF TO EDWIN M. HECKSCHER, OF BELLE HARBOR, NEW YORK.

PHONOGRAPH.

Application filed September 14, 1920. Serial No. 410,324.

To all whom it may concern:

Be it known that I, CARL J. HOFMANN, a citizen of the Republic of Germany, residing at and whose post-office address is 546 5 East 138th Street, city of New York, county of Bronx, State of New York, have invented certain new and useful Improvements in Phonographs; and I do hereby declare the following to be a full, clear, and exact description of the invention, such as will enable others skilled in the art to which it 10 pertains to make and use the same.

The invention relates to certain new and useful improvements in phonographs and 15 more particularly in the mode of attaching and supporting the horn or amplifier within the cabinet, so that the sole contact between the horn and the other elements of the phonograph is by means of a relatively loose 20 connection between the upper end of the horn and the under side of the tone arm support or other fixed part of the frame, preferably in the form of a slip joint which admits of the horn being readily applied 25 and removed or substituted by a horn of different character, the particular advantages of such an arrangement being the substantial elimination of all noises or sounds, incidental to the operation of the machine, except 30 the sounds specifically designed to be reproduced, which latter are delivered and amplified by the horn with the fullness and integrity of tone and quality which have not been capable of realization with machines of the standard type, in which the 35 horns are usually rigidly attached to the casing or cabinet at various points and which, therefore, transmit all of the sounds and noises produced by the operation of the 40 motor and other movable parts of the mechanism, to the serious impairment of the reproduction of the phonograph record.

One exemplification of the invention is illustrated in the accompanying drawings, in 45 which:—

Fig. 1 is a side elevation, partly in section, of a cabinet phonograph having the improvements aforesaid associated therewith;

Fig. 2 is a perspective view of the horn 50 and one element of the slip joint for connecting or suspending the same within the cabinet;

Fig. 3 is a fragmentary rear elevation 55 showing the joint between the horn and its support.

Referring to the drawings, 1 indicates the cabinet or casing of the phonograph, which may be of any of the usual or standard styles, sizes or shapes, provided with a hinged top 1' below which is located the 60 motor board 2, which is fastened to the inner walls of the cabinet in the usual manner, and supports the standard type of motor mechanism, record table and tone arm. The tone arm 3, which is more or less conventionally illustrated, is mounted on the upper face of the motor board 2 above the opening 2' therein. As shown, the cabinet is provided with doors at both front and back.

It has been customary heretofore to secure 70 the horn or amplifier to the under side of the motor board or tone arm support, or directly to the end of the tone arm by a rigid connection, with the result that any sounds or noises developed by the operation of the machine 75 were transmitted by the tone arm, the support therefor and the other elements of the casing or housing to the horn or amplifier, from which they were delivered with the sounds reproduced from the phonographic record, to the material and objectionable impairment thereof. It frequently occurred therefore that a substantially perfect record would be evidenced by harsh and unnatural tones and associated with strange 80 and unusual sounds which were characteristic of the particular machine. These objectionable characteristics were accentuated to even a greater degree in phonograph machines in which the horn or amplifier is attached to the body portion of the casing, in addition to the attachment thereof to the tone arm supporting board or to the end of the tone arm. The present invention is 85 designed to overcome all of these difficulties 90 and to provide the ordinary standard type of phonograph with a horn or amplifier which will deliver only the intrinsic values of the phonograph record, whether the same represent spoken words, vocal or instrumental tones, or any other character of sound, and which will not either receive or transmit the objectionable sounds or noises developed in the machine. To this end the horn or amplifier 7 includes a neck portion 5 to 105 the outer end of which is secured a block 6 having bevelled sides adapted to engage corresponding bevelled edges of strips of battens 4, 4 fastened to the under side of the motor board 2 adjacent the opening 2' there-

110

in, below the tone arm 3. The horn proper hangs free within the cabinet and is not in contact with any other part of the apparatus, so that it will be free from sounds or 5 noises developed in or transmitted by the cabinet or housing, or any part thereof. The connection therefore between the horn or amplifier and the other parts of the apparatus is solely through the relatively loose 10 slidable joint or attachment between the horn and the interior portion of the cabinet adjacent the end of the tone arm. This loose joint in itself, while properly supporting or suspending the horn, nevertheless is 15 effective to suppress and prevent transmission of any of the so-called machine noises, developed outside of the record, to the horn or amplifier. On the other hand, the character of the joint does not in any way impair 20 the free passage of the sound waves developed at the reproducer and conveyed through the tone arm, thence into the neck of the horn, but on the contrary the tones or sounds reproduced from the record are delivered by the horn or amplifier with all of 25 their original purity, fullness and integrity. The result is characteristic not only of spoken or singing voice records, but also of records of various musical instruments, and 30 the improvement in the quality, tonic effects and general excellence of reproduction, as compared with the former types of horns or amplifiers, is most striking and marked.

The horn or amplifier may be made of any 35 suitable and desirable material and in any preferred form, and the removable character of the horn admits horns of various types and materials being substituted to suit the particular record being reproduced. Likewise 40 the outlet of the horn may be directed toward any particular portion of the cabinet or casing, so that the invention is applicable to various standard types of casing and the present horn or amplifier may be substituted 45 for the older forms of these devices, in many instances, by merely supplying the under side of the motor board, tone arm support or

other proximate part of the cabinet with the complementary portion of the slidable joint by means of which the horn is suspended, as 50 indicated.

It will be obvious, of course, that the various other types of relatively loose joints between the horn of the motor board may be substituted, to the same desirable effect and 55 it is to be understood that the particular form of dovetailed joint as illustrated is merely exemplary.

As suggested, the horn or amplifier which is detachable or replaceable may be given 60 any desired form, shape or configuration. The relatively simple form illustrated in the drawings, in which the horn extends downwardly in a vertical direction from the motor board, takes up a relatively small 65 amount of space in the casing and leaves a much larger element of the casing space for storage of records as indicated.

It is frequently desirable that the amplifier be associated with a sounding board, and 70 such an arrangement is shown in the drawings, the sounding board usually being mounted on the rear wall of the partition 8 that forms the back of the record storage space, said sounding board being attached 75 to the partition 8 by means of spacing washers 10 and screws 11.

What I claim is:

1. A phonograph having a horn or amplifier depending below the tone arm, and 80 means for supporting the horn solely from the neck thereof comprising a horizontally slidable separable joint between the neck of the horn and the motor board.

2. A phonograph having a horn or amplifier depending below the tone arm, and 85 means for supporting the horn solely from the neck thereof comprising a horizontally slidable separable joint between the neck of the horn and the under face of the motor 90 board.

In testimony whereof I affix my signature.

CARL J. HOFMANN.
